UNITED STATES PATENT OFFICE.

JOHN G. BECK AND VICTOR F. BLAKESLEE, OF PITTSBURGH, PENNSYLVANIA.

BALLAST CLEANING AND REPLACING MACHINE.

Application filed January 18, 1926. Serial No. 82,039.

The purpose of the present invention is to provide a machine which will dig and pick up rock ballast outside of the ties on railroad road beds, remove the dirt that has been accumulated in this ballast, and return the clean ballast to the approximate position in the road bed from whence it was picked up, and deliver the débris in the same operation to cars for its convenient removal.

10 This invention will also return the clean ballast to its position within the space occupied by the ties in the road bed, which has been removed by laborers from between the ties working ahead of the machine, and placed outside of the ties.

15 Another object of the present invention is to provide a machine which can be quickly withdrawn from the adjacent railroad tracks and accommodate the passing of traffic thereon.

20 Another purpose of this invention is to reduce greatly the cost of cleaning railroad road beds per mile, and to increase the speed of performing this cleaning and replacing operation.

25 The present machine, it will be seen as the description proceeds herein, can be operated from air, steam, or other power, carried on or supplied by the locomotive which is attached to the present machine, or by local power units. A secondary use of the present machine is for the removal of snow in railroad yards and in some cases, where it is desirable to entirely remove cinder ballast road beds, and replace same with rock ballast, the machine can be used to remove entirely the cinders from the road bed.

30 In the accompanying drawings, forming part of the present specifications, I have shown one complete example of the embodiment of my invention constructed according to the best mode I have so far devised for the practical application of the principles of my invention. In the drawings:—

35 Fig. 1 is a side elevation of the ballast cleaning and replacing machine.

40 Fig. 2 is a transverse vertical section of Fig. 1, taken on line 2—2 thereof.

Fig. 3 is a top plan view of Fig. 1.

45 Fig. 4 is an enlarged plan view of a portion of Fig. 1, showing the mechanism used for lifting and withdrawing the scoops of my invention.

50 Fig. 5 is an enlarged partial end view of my invention taken from the left of Fig. 1.

55 Figure 6 is an enlarged partial plan view,

illustrating a means for holding the scoops shown in Figure 4, in an elevated position.

Figure 7 is a transverse vertical section on line 7—7 of Figure 1.

In the present invention a machine is provided for digging, elevating, cleaning and replacing ballast in railroad road beds, which machine may be conveniently divided for purposes of description into the following parts, to wit:

A digging and ballast elevating mechanism—1, a ballast cleaning and delivery means—2, a means 3 for removing the débris which has been obtained in cleaning the ballast, an operating mechanism 4, for actuating the several parts of the invention, and a lifting means 5, for elevating the scoops used in the digging operation.

Each of these elements of the device above named will be described in order below.

The digging and ballast elevating mechanism 1, consists of a pair of scoops 6, 7, disposed on opposite sides of a flat car 8 as shown clearly in Figs. 1 and 3 of the drawings. 80 These scoops 6, 7, each have vertical walls 9, 10 and a bottom portion 11, which follows the contour shown in Fig. 1 dotted. These scoops are provided with a plurality of digging teeth 12, 12, and a bent metal plow 13, 85 as shown, and said teeth and plows are intended to dig into the road bed ballast outside of the ends 14, 14 of the ties 15, (see Fig. 5) when the scoops 6, 7 are in the lowered position shown in said Figs. 5 and 1.

90 As the car 8 is advanced along the tracks by a locomotive (not shown) from the right to the left, as seen in Fig. 1, it is seen that the scoops will dig up the ballast and due to the curved bottom 11 of said scoops, the ballast, consisting of trap rock and débris, is delivered at point 16 into the boot 17 of the elevator 98 as is readily understood. The scoops 6, 7 are mounted slidably upon the uprights 18, 19 for the purpose of elevating them to 100 the approximate level 20 of the floor of the car 8, as will be further described herein in the description of the lifting means 5 before mentioned. It will be seen that the elevators 98, 98 and boots 17, 17 are positioned within 105 the outside dimensions of the car floor 20 as seen in Fig. 3 and that the scoops are constructed with the portions 21 turned inwardly in order to deliver the ballast and débris in the boots 17, 17. The scoops 6, 7 with their plows 13, 13 protrude beyond the deck of the car 8 and in order to permit the passing of

traffic on adjacent railroad tracks, said scoops with their plows have to be elevated (see Fig. 1) on the uprights 18, 19 and then withdrawn inwardly toward the center of the car until 5 such plows 13, 13 are positioned within the limits of the car deck 20, as can be understood from an inspection of Figure 3 of the drawings.

The elevators 98, 98 are similar in construction, but made opposite hand, and the description of one will apply to both of them. The elevator 98 consists of a series of buckets 22, 22 mounted on an endless chain 23, the upper and lower ends of which operate 15 over suitable drums or sprockets 24, 25, the latter being suitably mounted on axes 26, 27 respectively. The power for driving the endless chains 23 is obtained from an engine 28, which will be described hereinafter, the shaft 20 26 preferably being the driven shaft as can be seen from inspection of Fig. 1 of the drawings. It will be seen that the ballast and débris, which has been deposited in the boot 17 from the scoops 6, 7 at points 16 before described will, when the elevator 98 is in operation, be delivered by means of the chutes 29, 29 into the hopper 30. From the above it will be seen that the digging and ballast elevating mechanism comprises then, the scoops 25 with their digging teeth and plows, and the pair of elevators just described with their accompanying boots.

The ballast cleaning and delivery means comprises the following parts. A hopper 30, 35 said hopper being slidably mounted on a supporting framework 32, having a plurality of uprights 33, 33, etc., which last are in turn mounted on the deck 20 of the flat car 8. In some cases it may be found advisable to use 40 a series of hoppers 34, 35, each having a screen forming the bottom of each hopper at points 36, 37, said hoppers being coupled together at points 31, 31, etc., so that such screens can be vibrated in unison. It will be seen that 45 a screen of a mesh size which will permit the retention of the largest sizes of rock ballast, can be used to form the bottom 36 of the hopper 34 thus permitting the smaller size of rock ballast and the débris to pass into the hopper 35 and on to the screen 37. The screen 37 can then be made of proper mesh size 50 as will permit only the débris to pass therethrough on to the inclined sides 38 of the chute 39, and be deposited upon the belt conveyors 40, 41 as is readily understood. It will be seen that the largest size of rock ballast 55 which has been cleaned in the hopper 34 will drop automatically as the hopper is vibrated into the chutes 42, 42 and be deposited on the railroad road bed both inside and outside of the ends 14 of the ties 15. It will also be seen that the next largest size of rock ballast which 60 has passed into the hopper 35 will also be deposited on the chutes 42, 42 and in like manner be distributed on the road bed. In this con-

nexion it is of course apparent, that the ends 43, 44 of the hoppers 34, 35 respectively are left open to permit the rock ballast to be shaken on to the chutes 42, 42 as described. The vibration or slideable reciprocation of 70 the hopper 30 is accomplished by means of two connecting rods 45, 45, which are connected to, and eccentrically mounted on the shaft 46, said shaft being adapted to receive its power from the engine 28 as will be further described hereinafter, as the description proceeds, in connection with the before mentioned operating mechanism 4. It is evident from an inspection of Figs. 1 and 3 of the drawings that as shaft 46 is revolved the connecting rods 45, 45 will be reciprocated and cause the vibration of the hopper 30 to be accomplished.

The débris removing means consists of two co-acting belt conveyors 40, 41 before mentioned, the conveyor 40 is mounted at points 47, 48 on the deck 20 of the car 8, as is readily understood. Belt 40 is of proper width as can be seen from Fig. 2 of the drawings to receive the débris which is deposited upon its upper surface by the walls 38, 38 of the chute 39. It will be seen that the belt conveyor 40 is provided with a gear 49, shown in Fig. 3 clearly, and that such gear 49 receives power by means of a belt 101, or otherwise from the gear 50, which is mounted on the shaft 51 of the engine 28 before mentioned. It is also seen that the belt conveyor 41 is mounted at point 52 on the floor of the car 8 and the opposite end of such conveyor is suitably mounted at a convenient point of support (not shown) on the car 53. It is also seen that the conveyor 41 is provided with a gear 54 (see Fig. 3) which is driven by means of a belt or otherwise from gear 55, which is mounted on the shaft 51 of the engine 28, from which it is evident that the belt conveyors 40, 41 can be continuously operated and driven from power furnished by the main engine 28 of my machine. It is apparent that the dirt which has been deposited on the upper surface of the belt 40 is redeposited on the upper surface of the belt conveyor 41 and in this way is delivered into car 53 for convenient removal.

The operating mechanism consists of the following parts. A main or driving engine 28, having the housings 56, 56 and a main drive shaft 51 mounted therein is provided and mounted on the floor 20 of the car 8. As 120 before described the shaft 46 receives power from the main drive shaft 51 by means of the belts 57, 57. The main engine also transmits power to the elevators 98 by means of belts 58, 58 as is at once understood from Figs. 5, 3 and 1, of the drawings. The main driving engine 28 also operates the shaft 59 by means of beveled gear 60 which is suitably connected to a complementary gear 61 on the main drive shaft 51. It will be seen from an 125 130

inspection of Figs. 3 and 4 of the drawings that the shaft 59 in turn is adapted to operate gears 62, 63 which inter-mesh with racks 64, 65 respectively. These racks are 5 rigidly mounted on a frame work 66, which will be described. It is also noted in passing that clutches are provided 67, 68 for disengaging the gears 62, 63 when it is desired to throw same out of operation. Attention 10 is called to the fact that the shaft 46, before described, is suitably mounted on supports 69, 70, 100 etc.

The scoop lifting means, which is adapted to elevate the scoops from their lowest position, as shown in Fig. 1, to the approximate elevation of the top 20 of the car 8 comprises the following parts. A pair of horizontally disposed members 71, 72 each comprising a pair of beams 73, 74 are used. These members 20 71, 72 are adapted to be reciprocated on the top surface 20 of the car 8 by means of the gears 62, 63 and racks 64, 65 (see Fig. 4). The beams 73, 74 are rigidly connected by means of the cross bars 75, 75 as shown. 25 These horizontal members 71, 72 are held in position by means of the Z-bars 76, 77 but said Z-bars permit of the inward and outward horizontal movement of the members 71, 72 as is readily understood from an inspection of Figs. 1 and 4 of the drawings.

Mounted on the beam 74 and extending from the surface 20 of the car 8 upwardly are the two uprights 18, 19, before mentioned in the specifications, and said uprights are suitably 30 strengthened and braced by means of the slanting members 78, 79, which last are carried by the beams 73, 74. The uprights 18, 19 are connected by means of the braces 80, 81 as shown, for stiffening purposes. Below 35 the floor 20 of the car 8, it will be seen that the uprights 82, 83 are placed in direct vertical line with the uprights 18, 19 respectively. These uprights 82, 83 are rigidly attached at 84, 84 to the body of the car 8.

Near their lower extremities said uprights 40 82, 83 are braced by means of the members 85, 86 to the horizontal beam 87, which last is rigidly mounted on the body of the car 8. On the scoops 6, 7 as seen in Figs. 1 and 4 45 clearly, is rigidly mounted a pair of castings 88, 89 by means of the rivets 90, 90. It can also be seen from Fig. 1 that two such castings 88, 89 are used in connection with each plow 6, 7. The castings 88, 89 are of a U 50 shape as clearly shown in Fig. 4, and have outwardly extending ears 91, 91 formed thereon, and adapted to slidably engage upon the inner faces of the uprights 82, 83, 18 and 19. Also mounted on the inner walls 9, 9 55 on each of the scoops 6, 7 at points 92, 92 are racks 93, 93. These racks each intermesh with the gears 94, 94, which are mounted on the shafts 95, 95 of a pair of small engines 96, 97, which last are carried by the horizontal 60 members 71, 72 before described. It is

evident that when the engines 96, 97 are properly operated that the gears 94, 94 will lift the racks 93, 93 and the scoops 6, 7 from their lowest position as shown in Fig. 1, to a point substantially above the floor level 20 70 of the car 8, the castings 88, 89 slidably operating against the uprights 82, 83, 18, 19, and holding the scoops in proper vertical position as said scoops are elevated.

Pawl 99, 99 are mounted on the supporting 75 struts 78, 78 in order to prevent retrograde movement of the scoops when once they have been elevated to any desired position. From the foregoing description of the main engine 28 and the scoop lifting means 5, it is readily 80 seen that by means of the engines 96, 96 either scoop can be elevated to the elevation of the floor 20 of the car 8 and withdrawn inwardly toward the center of the car 8 to such a point that the extreme outer ends of the plows 85 can be brought within the limits of the outline of the car 8, so that passing traffic on adjacent lines of railroad track can conveniently pass the machine in hand. In other words, the engines 96, 97 are adapted to lift 90 the scoops 6, 7 respectively while the main engine 28 by means of the shaft 59 and the racks 64, 65 is adapted to bring either or both the scoops 6, 7 within the outline of the car 8. 95

In connection with the chutes 42, 42 for delivering the cleaned ballast to the road-bed, same are constructed so that they are detachable from the machine, or any other suitable provision can be made to enable their outer ends to be brought within the outline of the car 8, as can be seen from an inspection of Figures 2 and 3 of the drawings, when it is desired to permit the passing of traffic on adjacent railroad tracks. 105

Operation.—From what has been said above the operation of the cleaning and replacing machine as a whole needs only a brief description, to connect the operation of the above named five different elements or parts 1, to 5 inclusive which co-ordinate to make up the whole machine. The cars 8 and 53 are coupled to a locomotive (not shown) and drawn along the tracks from right to left as seen in Figure 1 of the drawings. The 110 scoops 6, 7 are lowered into their lowest or any desired position similar to that shown in Figure 1. The forward motion of the car 8 causes the ploughs 13, 13 and scoops 6, 7 to engage the road-bed to a proper depth, on either or both sides thereof as seen in Figure 5. The ballast to be cleaned between the ties and within the ends 14, 14 of ties 15 is 115 previously thrown into the path of the scoops by laborers working ahead of the ballast cleaning machine, as is at once understood. The advance of the car 8 is a slow movement which enables the scoops and ploughs to pass the ballast material excavated to the boots 17, 17 of the elevators 98, 98; from which 120 125 130

point the ballast and débris is automatically elevated to the hopper 34. The cleaned ballast of large size is immediately delivered by the action of the vibratory screens and hoppers to the chutes 42, 42, and therefrom to the road-bed. In this connection it is seen that the cleaned ballast is delivered over the entire width of the road-bed, both within and without the ends 14, 14 of the ties 15 as seen in Figures 2 and 5. The smaller size ballast which is retained in the hopper 35 is delivered in like manner to the chutes 42, 42 and is deposited on the road-bed. Laborers following the cleaning and replacing machine then properly distribute the cleaned ballast over the road-bed, and tamp same into proper position between and about the ties. The débris which has been deposited on the belt conveyors 40, 41 is passed by the action of said conveyors into the car 53 for convenient disposal.

From the above description and drawings it is evident a very useful, practical and quickly operating machine is provided for the purposes hereinbefore mentioned in the preamble of the specification; a machine which greatly reduces the cost, and increases the speed of cleaning and replacing ballast in railroad roadbeds; same being a distinct departure in the art in which it is used, in comparison with the present slow, laborious and expensive methods in current use for performing the cleaning and replacing operation in hand.

We claim:

1. In a ballast cleaning and replacing machine, a flat car, a scoop lifting means, comprising a framework having a pair of horizontal members adapted to be slidably withdrawn toward the longitudinal center line of the machine, a pair of vertical uprights each rigidly mounted on one of the horizontal members, a pair of vertically disposed uprights extending below the first named uprights and in alignment therewith, rigidly mounted on the car body, a plurality of U-shaped castings adapted to slidably engage the aforesaid uprights, a pair of scoops each rigidly attached to a pair of the U-shaped castings, and means of raising and retracting said scoops and associated parts toward the center line of the machine.

2. In a ballast cleaning and replacing machine, a flat car, a scoop lifting means, comprising a framework having a pair of horizontal members adapted to be slidably withdrawn toward the longitudinal center line of the machine, a pair of vertical uprights each rigidly mounted on one of the horizontal

members, a pair of vertically disposed uprights extending below the first-named uprights, and in alignment therewith, rigidly mounted on the car body, a plurality of U-shaped castings adapted to slidably and reciprocally engage the aforesaid uprights, a pair of scoops each rigidly attached to a pair of the U-shaped castings, a vertically positioned rack mounted on each scoop, means adapted to engage the racks, and severally elevate the scoops, and means for retracting the scoops and associated parts toward the center line of the machine.

3. In a ballast cleaning and replacing machine, a flat car, a scoop lifting means, comprising a framework having a pair of horizontal members adapted to be slidably withdrawn toward the center line of the machine, a pair of vertical uprights each rigidly mounted on one of the horizontal members, a pair of vertically disposed uprights, extending below the first-named uprights, and in alignment therewith rigidly mounted on the flat car body, a plurality of U-shaped castings adapted to slidably reciprocate between the aforesaid uprights, a pair of scoops each rigidly attached to a pair of the U-shaped castings, a vertical rack mounted on each scoop, a pair of engines each adapted to engage one of the racks and lift the scoops, means for holding the racks against downward movement when in elevated position, and a main engine adapted to retract said scoops and associated parts toward the center line of the machine, while the scoops are held in an elevated position.

4. In a ballast cleaning and replacing machine, a scoop lifting means, comprising a framework having a pair of longitudinal horizontal members, a pair of Z-bars slidably engaging opposite ends of the horizontal members, an inwardly turned horizontal rack mounted on each of the latter members, a pair of vertical uprights forming guide-ways, each mounted on the car body and the aforesaid framework, a pair of scoops, each adapted to slidably engage in one of the guide-ways, means for vertically reciprocating the scoops in the latter, a main engine having a pair of pinion gears on its drive shaft, each engaging one of the horizontal racks above-mentioned, for the purpose of severally and simultaneously reciprocating the framework, and scoops to and from the center line of the machine.

In testimony whereof we affix our signatures.

JOHN G. BECK.
VICTOR F. BLAKESLEE.
